UNITED STATES PATENT OFFICE.

EDWARD A. WILLARD, OF NEW YORK, N. Y.

DESIGN FOR A CIGAR-CUTTER.

SPECIFICATION forming part of Design No. 34,365, dated April 16, 1901.

Application filed February 13, 1901. Serial No. 47,187. Term of patent 14 years.

To all whom it may concern:

Be it known that I, EDWARD A. WILLARD, a citizen of the United States, residing at New York, county of New York, State of New York, have invented and produced a certain new and useful Design for a Cigar-Cutter; and I do hereby declare the following to be a full, clear, and exact description of the invention, such as will enable others skilled in the art to which it appertains to make and use the same.

My invention is illustrated in the accompanying drawing, forming a part of this specification, and showing a perspective view of a cigar-cutter embodying the design claimed.

As shown in the drawing, the leading feature of the design consists of a base A, whose surface *c* and rim *a* form a cup-shaped recess, from which rises the central columnar struc-

ture *b* B C of the general configuration of a cartridge. Projecting from said cartridge-like structure are the stem *f* and button *D*, and the cartridge-like structure is furthermore provided with conical recesses *d d* and a subjacent recess *e*. The cross-hatching on the drawing indicates milled surfaces.

Having described my invention, what I claim as new, and desire to secure by Letters Patent, is—

The design for a cigar-cutter, as herein shown and described.

In testimony whereof I affix my signature in presence of two witnesses.

EDWARD A. WILLARD.
